UNITED STATES PATENT OFFICE.

WILLIAM J. TUNMORE, OF GRAND RAPIDS, MICHIGAN, ASSIGNOR TO
WILLIS J. PERKINS, OF SAME PLACE.

SHINGLE-SAWING MACHINE.

SPECIFICATION forming part of Letters Patent No. 369,668, dated September 6, 1857.

Application filed November 23, 1886. Serial No. 219,660. (No model.)

To all whom it may concern:

Be it known that I, WILLIAM J. TUNMORE, residing at Grand Rapids, in the county of Kent and State of Michigan, have invented 5 certain new and useful Improvements in Shingle-Sawing Machines, of which the following is a specification, reference being had therein to the accompanying drawings.

This invention relates to shingle-sawing machines; and it consists in certain improvements in the bolt-carriage and in the mechanism for beveling the ends of shingles heretofore invented by Willis J. Perkins, of Grand Rapids, Michigan.

15 In the drawings, Figure 1 is a broken side elevation, partly in section, of so much of a shingle-sawing machine as is necessary to illustrate my invention. Fig. 2 is a section of part of the carriage and wooden dog or bearing-block. Fig. 3 is a plan of mechanism shown in Fig. 1. Fig. 4 is a perspective view of the tilt-table with beveling-knives attached, and with the mechanism for giving movement to the tilt-table. Fig. 5 is an enlarged plan 25 of the dovetailed groove and block. Fig. 6 is a detail section showing beveling-knife. Figs. 7, 9, 10, and 11 are views showing modifications for holding the wooden dog or bearing-block. Fig. 8 is a plan of one of the movable dogs 30 with wooden bearing-blocks inserted.

A indicates the saw, B the driving-pulley, C the carriage-driving pulley, and D E the oscillating bar and pitman, by which the saw-carriage F is reciprocated, none of these parts 35 being of my invention.

The saw-carriage F has at the side farthest removed from the saw projecting ribs a a from the cross-bar b of the carriage.

Heretofore blocks of wood or soft metal have 40 been applied to the frame or dog of a shingle-sawing machine, and have been secured by a loop or strap passing over the face of the block. This was objectionable, as it did not present an entire surface of wood toward the shingle-bolt, and gave a projection on which the bolt might rock. In the present invention the adjustable wooden or equivalent soft metallic block is secured to the face of the carriage or end of dog, or both, by a dovetail tongue and 45 groove or the equivalent of such construction. Some of the various modifications the tongue

and groove may take are shown in the drawings.

As shown in Figs. 2, 3, and 5, ribs a are cast or otherwise secured on the cross-bar b of the frame, so as to project toward the position the bolt is to occupy. Between these ribs I insert a wooden or other soft metallic block, d, having a dovetailed portion or tongue which enters between said ribs and fits closely enough to 60 hold the block firmly with the entire surface toward the shingle-bolt free from projection or from any metallic part which can bear against the shingle-bolt. This firm bearing of the wooden or soft metallic pushing or bearing 65 block against a shingle-bolt is of great use in preventing the last end of the bolt or spalt from working back under the carriage and thereby permits of the cutting of the bolt up closer or with less waste.

In Figs. 7, 9, 10, and 11 the block d is shown as presenting its entire face toward the belt. In Figs. 7, 9, and 10 the bar b has a groove cut in its face, instead of having forward-projecting ribs. In Figs. 9 and 10 a metallic tongue, e, is secured to the block and enters the groove in the frame, while in Fig. 11 the metallic tongue is secured to the block and enters a groove in the frame. In Fig. 8 the block is shown as applied to one of the 80 dogs, V, instead of to the frame of the carriage, the dog V having an angle-piece, V', extending inside the carriage-frame. All these constructions I consider as practically equivalent and within the scope of my invention. In 85 Fig. 8 the end of the dog has a groove cut into it for holding the block of wood or soft metal. It will be understood that this form of block may be applied to any of the various forms of shingle-machines for which it is adapted without departing from the spirit of my invention.

L represents the tilt-table of the sawing-machine, the same being of the general construction invented by said Perkins, and attached 95 to the machine in the usual manner, so as to receive the shingle-bolt as it is loosened from the dogs of the carriage, and to tilt so that the machine will saw alternately butts and points from the shingle-bolt.

On the outer bars or ways, l, of the tilt-table I place bosses m, constituting carriers or

stocks for the blades or knives *n*. These knives are at the forward end of the tilt-table—that is, the end toward the saw. The knives stand, preferably, at an incline relative to the top of the tilt-table, and are preferably inclined on the edge, so as to give a draw cut. The knives *n* may be secured in their seats in the stocks *m* by set-screws *o*, or by other suitable and equivalent mechanism, and their upper edges should be so adjusted as to project up to a level with the saw.

When the shingle-saw carriage *F*, with the contained bolt *H*, is forced forward toward the saw, the lower face of the bolt will be cut by the knives in an inclined direction at about the corner of the shingle-bolt, thus giving a bevel to the lower end edges of the shingle-bolt if the bolt be of just and proper length, or scoring just within the ends if the bolt be a trifle long. The cut or score at the end of the bolt which is to constitute the shingle-butt will be at least as deep as the thickness of said butt. If it be a trifle deeper, the saw-kerf will leave the bottom of the bolt smooth after the sawing.

By this arrangement of knives of the tilt-table or some other part of the frame which has no forward movement toward the saw the shingles can be cut of a uniform length and the ends beveled at any desirable angle before they are severed from the bolt. It is evident that the process of sawing will be in nowise retarded by the cutting, provided the carriage be driven with sufficient power to keep the machine up to the normal or desired rate of speed with reference to the saw.

The knives can be readily removed for sharpening, and by means of inserted pieces or wedges *p* in the knife stock or socket may be varied in distance from each other.

It will be understood that the ends of the shingle-bolt are dogged in the carriage above the plane of the cut of the knives, so that the knives will not cut against the dogs.

It will be also understood that the same principle of operation applies to shingle-machines having saws on horizontal arbors, and that slight changes and the substitution of equivalents may be made without departing from the spirit of this invention.

I claim—

1. The combination, with the carriage of a shingle-sawing machine, of a block of wood or similar material adjustably secured in the carriage at the side of the carriage farthest from the saw-arbor, and having its face toward the shingle-bolt uncovered toward the periphery of the saw so as to crowd the shingle-bolt onto the rim of the saw, substantially as described. 55

2. A shingle-saw carriage having grooves in its inner face, (or in similar position in the dog, as described,) combined with removable blocks of the character described held in said grooves, the blocks presenting their uncovered working-faces toward the saw-arbor, substantially as described. 60

3. The combination, with the saw-carriage having grooves in its side farthest from the saw, of a metallic tongue entering said groove and a block of wood or equivalent material 70 secured to said tongue so as to present the working-face of the block toward the saw-arbor.

4. In a shingle-sawing machine, a power-driven carriage having clamping-dogs, a tilt-table on which the shingle-bolt is adjusted, and knives fixed relatively to the forward and backward movement of the carriage and extending into the line of movement of the bolt carried by the carriage, substantially as described. 75

5. The combination, with the tilt-table of a shingle-sawing machine, of the cutting-knives secured thereto and extending into the path of movement of the shingle-bolt toward the saw. 85

6. The tilt-table having knife-seats attached to the ways thereof, in combination with knives adjustably secured in said knife-seats, substantially as described. 90

7. The combination, in a shingle-sawing machine, of the tilt-table having knives therein and the power-driven carriage having dovetail blocks secured therein at the side opposite the knives when the carriage is drawn away from the saw. 95

In testimony whereof I affix my signature in presence of two witnesses.

WILLIAM J. TUNMORE.
